VANITY CASE

Filed Aug. 7, 1929

John L. McAttee, INVENTOR
Rufus Saenger & Rice Kennedy, BY
H. H. ATTORNEYS

UNITED STATES PATENT OFFICE

JOHN L. McATREE, OF BROOKLYN, NEW YORK, ASSIGNOR TO SCOVILL MANUFACTURING COMPANY, OF WATERBURY, CONNECTICUT, A CORPORATION OF CONNECTICUT

VANITY CASE

Application filed August 7, 1929. Serial No. 384,129.

This invention relates to certain improvements in vanity cases or boxes.

These vanity cases are usually small metal containers capacitated to hold cosmetics and are of a small size so as to be conveniently carried in ladies' pocketbooks, handbags or the like. Certain types of these cases are arranged to hold cosmetics in the form of compacts, as rouge or face powder. These 10 compacts are usually made by moulding the powder onto plates of light metal or glass, which are held in the cases in a variety of ways. However held, it is desirable that these compacts be readily removable when 15 they are used up so that fresh compacts can be substituted therefor. In marketing these cases and compacts, a dealer will frequently have a case with compacts of a certain kind of powder and the customer while liking the 20 case will often desire a different kind of powder. It is desirable, therefore, that the compacts may be quickly and readily removed and others substituted, the means by which the compacts are held in place being such 25 that full compacts may be removed from the case without injuring the compacts.

It is the special object of the present invention to provide a vanity case or box having provision for carrying compacts which 30 are so constructed and arranged that full compacts may be removed from the box and others substituted without injury to the compacts, and a box in which used compacts may also be quickly and readily removed and other 35 substituted therefor by the user.

A further object of the invention is to provide a box in which the compacts are carried on a hinge member so that any danger of dropping the compact carrier while changing the compact is eliminated.

A further object of the invention is to provide a vanity box or case in which the details of construction are improved and a box of 45 small form and of attractive appearance.

With these and other objects not specifically referred to, the invention consists in certain novel parts, arrangements and combinations which will be described in connection with the accompanying drawings and the

novel features pointed out in the claims hereunto appended.

In these drawings,—

Figure 1 is a top view of the improved box shown open;

Figure 2 is a central sectional view of the box shown in Figure 1, the section being taken on line 2—2 of that figure;

Figure 3 is a side view of the box with the compact carrier partition or frame raised to compact expelling position;

Figure 4 is a top view, partly broken away, of an improved catch mechanism which may be used in the case;

Figure 5 is a detail sectional view of the hinge construction for uniting the body and the cover of the case, the section being taken on line 5—5 of Figure 2, and

Figure 6 is a detail sectional view taken on line 6—6 of Figure 2.

Referring now to these drawings, the case selected to illustrate the invention includes a body, a cover, and an intermediate compact carrying partition pivotally associated with one of these parts, the body shown being of light metal and rectangular in section. It will be understood, however, that the invention is not to be limited to this shape of box, but that as to certain of its features the invention may be used in boxes of widely varying characters.

Referring, however, to the box illustrated, this box includes a rectangular body 1 having side walls 2, and this body is closed by a cover, indicated generally by the numeral 3 and more fully hereinafter referred to.

Pivotally associated with the box is a partition or frame member which forms one of the important features of the present invention. In the particular construction shown, this member is rectangular in shape and dimensioned to fit snugly in the bottom of the box when in closed or compact holding position, but may be readily swung outwardly from the body so that the compact may be easily and quickly removed therefrom. This partition or frame includes side walls 4, 5, a front wall 6, and a back wall 7, and extending inwardly from

these walls is a narrow base flange 8, this flange extending around the frame. Intermediate its front and back walls is a partition base flange 9, and seated on this base 5 is a partition plate 10 which divides the frame into two compartments 11, 12, capacitated to hold powder and rouge. This partition plate 10 may be held in position in any suitable manner, as by nibs, indicated 10 at 13, engaging the side walls 4, 5 of the frame.

It will be observed that the compartment 11 is smaller than the compartment 12, and is designed to hold a rouge cake 14, the compartment 12 holding a powder cake 15, the reason for this construction being that the powder is more rapidly used than the rouge.

In the best constructions a separate cover 20 is provided over the rouge compartment 11, this cover being marked 16 and being preferably pivotally associated with the partition 10 on hinges 17 conveniently formed by slitting the metal of the plate as at 18 and then turning over extensions 19 formed on 25 the cover to form hinged knuckles. If desired for convenience, the front edge of the cover 16 is cut away as indicated at 20 to permit its easy lifting by the finger of the user.

30 As before stated, the cover and the compact holding partition frame are pivotally associated. While the specific means for effecting this may be, of course, varied within wide limits, in the particular construction shown and described, the back wall 2 of the box is slit at spaced points and the metal of the slits is turned over to form hinged knuckles 21, 22 (Figure 5), and the back wall 7 of the partition is formed with an 35 offset tongue 26, which is bent over to provide a hinged knuckle 27. A pintle pin 28 is passed through the knuckles 21, 22 and 27 and the ends of this pin are passed through apertures 28' formed in a flanged 40 member 29 carried by the cover 3 and more specifically hereinafter referred to, the ends of the pintle pin being bent around toward each other as indicated at 30 in Figure 1, the three parts of the box thus being pivotally 45 associated in a very simple and convenient manner.

50 It will be noted that the bottom of the compact-carrying partition frame is open so that, when the frame is swung on its pivot, 55 the compacts can be readily forced past holding nibs 32, 33 by which they are held in place in the frame, thus making it very easy to remove used compacts and substitute others. Furthermore, by associating the 60 compact-carrying frame with the other parts of the box, this frame cannot be dropped and thus have a liability of injuring the compacts. Furthermore, the compacts can be readily and quickly changed 65 by the seller to suit the convenience of the

user, when the user desires certain cosmetics other than those that happen to be present in the box when purchased.

In the best constructions, the box will have a mirror associated therewith and this mirror may be held in position in various ways. In the particular construction shown, the member 29 before referred to, includes a vertical flange 34 and a flat flange 35 inset therefrom by which the member may be secured to the box-cover, which in the particular construction shown, is a flat sheet of metal, either by soldering or spot welding, or in any other suitable way. This flange member forms a seat for the mirror 36 which may be held in position by a bezel 37, which has a close frictional fit with the vertical flange 34 of the member 29.

70 The body and the cover of the box are provided with complementary catch members of improved construction for holding these bodies in closed relation when not in use. While the specific construction of these catch members may vary within certain limits, in the particular construction illustrated, the 75 front wall 38 of the flange 35 before referred to, is formed with a pair of spaced flat tongues 39, 40, which act as guides for a catch member shown in the form of a flat plate 41 which has a finger extension 42 projecting through 80 an aperture 43 in the front vertical wall of the flange 34 and this catch member is formed with a lip 44, arranged to engage in a notch 45 in the front wall of the bottom of the box; this lip extending through a cutout 44' 85 in the bezel 37, before referred to. This catch plate is preferably spring-controlled and also preferably has a slight tipping movement. As shown, it is formed with a pair of spaced 90 half rounds 46, 47, in which engages a spring wire 48, the ends of this spring wire being held in position under half rounds 49, 50 formed by turning up the metal of the flange 38, before referred to.

95 It will be observed that with the construction shown and described a thin box of attractive appearance has been provided, one in which the compacts may be readily changed as desired, and one in which the construction of the parts has been improved and 100 simplified. Furthermore, the construction is such that the rouge and powder now are effectively separated, so that there is no danger of the rouge coming in contact with the powder, and a readily usable box provided, 105 and it will be understood, of course, that in the present box, suitable puffs or other applicators may be provided over the powder and rouge.

110 While the box has been shown in its preferred form, it will be understood that certain changes and variations may be made in the specific construction and arrangement of the box without departing from the invention as defined in the appended claims.

What I claim is:

1. In a vanity case, a body, a cover, a hinge pivotally uniting these parts, a frame divided into compartments lying in the same plane and having open bottoms pivotally associated with the body, means for holding compacts in the frame, and means for holding the body and cover closed with the frame entirely within the body and resting on the bottom thereof.

2. In a vanity case, a body, a cover, a hinge pivotally uniting these parts, a frame pivotally mounted on the same hinge, a partition dividing the frame into compartments lying in the same plane and open at their bottoms, means for holding compacts in the frame, a second cover pivotally secured to the partition and closing one of the compartments, and means for holding the body and cover closed with the frame entirely within the body and resting on the bottom thereof.

3. In a vanity case, a body, a cover, a hinge pivotally uniting these parts, a partition frame divided into compartments having open bottoms each surrounded by an inwardly directed flange, means for hinging the frame in the case so that it will lie in the body when the box is closed but may be swung out from the body to expose the bottoms of compacts held in the compartments, and a catch for securing the body and cover in closed relation.

4. In a vanity case, a body, a cover, a pintle hinge pivotally uniting these parts, a partition frame divided into compartments having open bottoms each surrounded by an inwardly directed flange, means hinging the frame in the case so that it will lie in the body when the box is closed but may be swung out from the body to expose the bottoms of compacts held in the compartments, a second cover pivotally associated with the frame to close one of the compartments, and means for holding the body and its cover in closed relation.

5. In a vanity case, a body, a cover, a hinge pivotally uniting these parts, a frame pivoted in the case having inwardly extending bottom flanges and a cross flange, a partition bar resting on the cross flange and dividing the frame into compartments, and a cover pivoted to the partition bar and closing one of the compartments.

55 In testimony whereof, I have hereunto set my hand.

JOHN L. McATREE.
